REEL HUB

Gerald D. Cohen, Massapequa, N.Y., assignor to Potter
Instrument Company, Inc., Plainview, N.Y., a corpora-
tion of New York

Filed Nov. 12, 1963, Ser. No. 77,362

Term of patent 14 years

(Cl. D61—1)

The figure is a perspective view of a reel hub showing my new design. The fragmentary, broken-line showing of a reel is for illustrative purposes only. The rear of the reel hub, not shown, is plain and unornamented.

I claim:

The ornamental design for a reel hub, as shown and described.
